CONTROL METHOD AND APPARATUS FOR
ARC DISCHARGE

Louis R. Noffsinger, Alexandria, Va.

Application April 17, 1951, Serial No. 221,493

10 Claims. (Cl. 315—357)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to electrode assemblies for arc lamps and the like generally, and more particularly, to a method and apparatus for maintaining a point of arc discharge in fixed relation between arcing electrodes.

Various types of electrode assemblies are used in arc lamps and similar types of equipment to establish a source of light or heat and other useful forms of electrical energy. Such electrode assemblies usually take the form of spaced consumable electrodes connected in circuit relation with a suitable source of electrical power and including means for feeding the electrodes relative to each other. The prior art suggests various methods and apparatus for controlling the feed of the individual electrodes and for indirectly controlling the point of discharge of the arc between the electrodes in such assemblies.

Methods and apparatus of the latter type operate on the principle of recognition of or indirect reaction to arc displacement by some sensitive means, such as a visual or thermo-electric element, which transforms and relays the effect of such recognition or reaction to a suitable electrode control mechanism. Such elements are usually spaced from the arc so that the recognition or reaction is indirect with the attendant disadvantages of time lag and lack of sensitivity.

It is an object of this invention to provide a method of maintaining a predetermined relation between arcing electrodes and the position of an arc discharge therebetween in direct response to displacement of the arc discharge from the predetermined relation.

Another object of this invention is to provide a simple and economical electrical control apparatus which responds directly to arc displacement by contact therewith to maintain a fixed relation between the position of arc discharge and arcing electrodes.

A further object of this invention is to provide a method of controlling movement of an arcing electrode in direct response to arc displacement to maintain the position of arc discharge in fixed relation between the arcing electrodes.

Briefly, in accordance with this invention, there is provided a method and apparatus for maintaining a fixed relationship between movable electrodes and the arc discharge therebetween by establishing an electrical contact in the nature of a probe adjacent the arc and connecting said probe through a suitable electrically controlled drive to effect movement of a movable electrode

2

consequent upon energization of the control circuit by contact of the probe with the arc. The shifting of the arc in any direction from its initial point of discharge from a movable electrode will energize the control circuit to move the electrode in a direction to restore the arc to its initial relative position between the arcing electrodes.

In the drawings, Fig. 1 illustrates an electrode assembly and associated control probes and driving mechanism; Fig. 2 is an end view of the electrodes and associated control probes; and Fig. 3 is a side view illustrating the preferred alignment of the electrode assembly and control probes in the embodiment of Fig. 1.

Referring now to Fig. 1, there is provided an electrode assembly having a circular or disc type electrode 1 which is mounted for rotation on a driving shaft 2 and coupled at 3 to a suitable electrical reversible motor enclosed in the control box. The disc electrode 1 is normally stationary and is rotated only for purposes of arc position control as will be hereinafter described. In the embodiment of Fig. 1, the disc electrode 1 may be designated as a negative electrode, which operates in the electrode circuit of the assembly to establish a point of arc contact between a rod type positive electrode 4 and a suitable source of unidirectional electrical power diagrammatically represented in the circuit. The rod type electrode 4 is mounted in a predetermined fixed relation to the disc type electrode 1 and may be supported in such position on a suitable mounting 10.

Once the arc has been established between the electrodes 1 and 4, optimum operation of the electrode assembly requires that the arc discharge from the continuous negative electrode surface remain fixed relative to the rod type electrode. Such fixed relationship results in uniformity of arc energy content and aids efficient utilization of electrode surface. In practice, it has been found that in such an arrangement the point of discharge of the arc has a tendency to shift primarily because of the continuous arc surface from which the arc is initiated. Such arc shift or displacement results in undesirable variations in arc energy content and operation. Other factors that may contribute to such arc displacement are the consumption of electrode surface, variations in applied energy and electrode material, and variations in atmosphere in the arc area.

Such undesirable variations can be reduced in accordance with the preferred embodiment of this invention by suitably supporting an electrical arc conductor in the form of a probe 5 adjacent the electrode discharge surface in spaced relation from the arc and the surface. In the preferred embodiment, a pair of probes are preferably posi-

tioned on opposite sides of the arc as shown in Figs. 2 and 3. The probes 5 may each be connected electrically to a control circuit or the control fields of a reversible electrical motor through suitable terminals 7 and 8, respectively, mounted on the control box as shown in Fig. 1. A common return is provided for each of the probes from the terminal 9 to the rod electrode 4. The motor or other electrode drive is thus connected in an energizing circuit through either of the probes 5 in shunt across the normally open arc path to a particular probe. These connections are such that the circuit established through either probe will energize the reversible motor in opposite directions. Accordingly, should the arc discharge in Fig. 1 shift along the continuous negative electrode surface an amount sufficient to contact the probe circuit on the side of the arc shift, a control circuit would be established through the rod type electrode, the arc, and the probe contacted to the reversible motor. The voltage appearing between the rod electrode and the point in the arc flame touched by a probe is applied to the control box at terminals 7 and 8 which are in turn connected to a reversible motor or similar device as hereinbefore described. The motor or drive is connected in the circuit to be energized to rotate the shaft 2 and disc type electrode 1 in a direction away from the probe contacted, thereby shifting the point of arc discharge out of contact with the probe towards its initial position and opening the energizing circuit across the probe arc path to the motor. The disc electrode 1 remains stationary until the arc discharge again shifts to repeat the cycle in either direction.

Thus, in accordance with the preferred embodiment of this invention, any shifting of the point of arc discharge along a continuous negative electrode surface will be corrected by movement of such surface in a direction to maintain the point of arc discharge fixed relative to the other electrode. Such control serves to maintain a predetermined or fixed relationship between the position of the arc discharge and the arcing electrodes in electrode assemblies or the like. The manner of energizing the electrode control means by direct electrical contact with the displaced arc results in a simple, direct-acting, and highly sensitive control for maintaining the desired arc discharge position.

The method described herein contemplates the establishment of a direct electrical arc contact as a boundary to limit displacement of an established arc between arcing electrodes. Violation of established boundary conditions by arc displacement sufficient to contact a probe boundary will be reflected in a control circuit energized by such contact to move the electrode from which the arc is displaced in a direction to restore the arc to its initial discharge position and thereby break the contact to deenergize the electrode moving means.

Accordingly, the principle of this method may be applied to any electrode arc assembly regardless of form and irrespective of independent electrode feeds. By way of further example, the electrode assembly may comprise a pair of disc-type electrodes having probe contact controls connected to the respective electrode drives to maintain the desired arc relation between such electrodes.

I have shown and described what I consider to be the preferred embodiment of my invention along with suggested modified forms, and it will be obvious to those skilled in the art that other

changes and modifications may be made without departing from the scope of my invention as defined by the appended claims.

Having thus described my invention, what I claim as new and wish to secure by Letters Patent is:

1. In an arcing electrode assembly including a movable continuous electrode surface and another electrode spaced in fixed relation therefrom, electrically controlled means for moving said continuous electrode surface relative to said other electrode, an arc conductor positioned adjacent said movable electrode surface in spaced relation from the arc and said surface, and means connecting said electrode moving means through said arc conductor and across the normally open arc path to said arc conductor, the said arc conductor being adapted to be contacted by the arc to energize said moving means consequent upon displacement of the arc towards contact with said conductor to move the electrode surface in a direction to restore the displaced arc to its initial position relative to the other electrode and thereby break contact with said conductor.
2. In an arcing electrode assembly including a movable continuous electrode surface, electrically controlled means for moving said electrode surface relative to another electrode spaced in fixed relation relative to the continuous movable electrode surface, an arc conductor positioned adjacent said movable continuous electrode surface in spaced relation from the arc and said movable continuous electrode surface, a normally open circuit connecting the electrically controlled moving means through the arc conductor and across the normally open arc path, the said arc conductor being adapted to be contacted by the arc to energize said moving means consequent upon displacement of the arc towards contact with said conductor to move the electrode surface in a direction to return the displaced arc to its initial position relative to the other electrode.
3. In an arcing electrode assembly including a pair of electrodes arranged for passage of an arc therebetween, means for moving one of the electrodes, an electrical control circuit for the movable electrode having a point of direct electrical arc contact positioned adjacent the normal arc path between the said pair of electrodes and spaced therefrom, said point of electrical contact adapted to be contacted by the arc consequent upon displacement of the arc from its normal path between the pair of electrodes and towards the said point of arc contact to energize the control circuit and move the movable electrode in a direction to return the displaced arc to its initial normal path between the said pair of electrodes.
4. In an arcing electrode assembly including a movable continuous electrode surface, electrically controlled means for moving said electrode surface in opposite directions relative to another electrode, a pair of arc conductors, each of said conductors positioned adjacent said electrode surface in spaced relation from the arc and said surface, and means connecting said electrode moving means in reversing relation through said conductors and across the normally open arc path to each conductor respectively, each of said arc conductors adapted to be contacted by the arc consequent upon displacement of the arc towards the respective conductor to energize the electrode moving means and move the electrode surface in a direction to return the displaced arc to its initial position between the electrodes.
5. An electrode assembly comprising in com-

bination, a pair of electrodes, means for establishing an arc between said electrodes, electrical means for moving one of said electrodes, the other electrode of the pair being fixedly mounted in spaced relation to the movable electrode, an electrical arc contact supported in spaced relation adjacent the point of arc discharge from said movable electrode to the fixedly mounted electrode, normally open circuit means connecting said electrical arc contact to said electrode moving means whereby said moving means are energized in a predetermined direction to return the arc to its initial position consequent upon arc displacement establishing the circuit through said electrical arc contact.

6. In an arcing electrode assembly, a disc type electrode, a rod type electrode cooperatively positioned in predetermined fixed relation relative to said disc type electrode, electrically controlled reversible means drivingly connected to said disc type electrode, a pair of electrical probes positioned in the plane of the disc electrode adjacent the arc path and spaced on opposite sides therefrom respectively, means reversibly connecting each of said probes respectively through the normally open arc path to each probe to energize said driving means, said normally open energizing circuit adapted to be energized by the arc consequent upon displacement of the arc towards contact with the corresponding probe to move the electrode in a direction to return the displaced arc to its initial position in the electrode assembly.

7. In an arcing electrode assembly having a rotatable disc type electrode and a rod type electrode spaced in fixed relation therefrom and including electrical means to establish an arc therebetween, reversible electric driving means operably coupled to said disc type electrode, a pair of electrode probes each positioned on opposite sides of the arc discharge and spaced therefrom adjacent the periphery of said disc type electrode, means connecting each of said probes with said electrical driving means across the normally open arc path to each probe respectively to effect rotation of the disc electrode in opposite directions consequent upon displacement and contact of the arc discharge with the corresponding probe.

8. An arcing electrode assembly comprising in combination, a disc type electrode, a rod type electrode suitably supported at a fixed spacing from said disc type electrode, electrically reversible driving means operably coupled to said disc type electrode, a source of power, circuit means con-

necting said source of power between said electrodes to establish an arc therebetween, a pair of electrode probes each positioned on opposite sides of said arc discharge and spaced therefrom adjacent the periphery of said disc electrode, means connecting each of said probes with said driving means across the normally open arc path to each probe respectively to energize said driving means in a direction to restore the arc to its initial position consequent upon displacement and contact of said arc discharge with a corresponding probe.

9. In an arcing electrode assembly including a movable continuous electrode surface and another electrode spaced in fixed relation therefrom, electrically controlled means for moving said continuous electrode surface relative to said other electrode, an arc conductor positioned adjacent said movable continuous electrode surface in spaced relation from the arc and said surface, and normally open circuit means connecting said electrode moving means in circuit relation between said arc conductor and the fixed electrode across the normally open arc path to said arc conductor to energize said moving means consequent upon displacement of the arc towards contact with said arc conductor, whereby said continuous electrode surface is moved in a direction to restore the displaced arc to its initial normal path between the movable continuous electrode surface and the fixed electrode and away from contact with said arc conductor.

10. In an arcing electrode assembly including a movable continuous electrode surface and another electrode spaced in predetermined relation therefrom, electrically controlled moving means for moving said electrode surface in opposite directions relative to said other electrode, a pair of arc conductors, each of said conductors positioned adjacent said electrode surface in spaced relation from the arc and said surface, and means connecting said electrode moving means in reversing relation between each conductor and said other electrode across the normally open arc path to each conductor respectively, each of said arc conductors adapted to be contacted by the arc consequent upon displacement of the arc towards the respective conductor, whereby said electrode moving means is energized to move said electrode surface in a direction to return the displaced arc to its initial position between the electrodes and away from contact with said conductor.
